UNITED STATES PATENT OFFICE.

ISAIAH McKNIGHT, OF LOUISVILLE, KENTUCKY.

HARNESS ATTACHMENT.

No. 835,549.

Specification of Letters Patent.

Patented Nov. 13, 1906.

Application filed May 3, 1905. Serial No. 258,648.

To all whom it may concern:

Be it known that I, ISAIAH McKNIGHT, a citizen of the United States, residing at Louisville, in the county of Jefferson and State of Kentucky, have invented a new and useful Harness Attachment, of which the following is a specification.

This invention relates to improvements in harness, and has for its object to provide a simply-constructed and easily-applied connecting structure between certain parts of the harness whereby increased efficiency and utility are secured, together with a material saving in the amount of leather required.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings thus employed, Figure 1 is a perspective view of the improved device. Fig. 2 is a longitudinal sectional view of the same.

The improved device may be employed at several different portions of the harness—such as between the hip-straps and breeching, between the cheekstraps and the bits or other parts of the headstall, between the "crotch-straps" and hames, between the side straps and trace-buckles, and the like—and consists of a strap having an aperture at one end and a buckle at the other end and folded intermediately and with means such as a ring inserted at the folded portion to connect to the member to be supported. A keeper is attached to the folded strap and firmly secured thereto and serves not only as a receptacle of the loose end of the billet of the strap engaged by the buckle, but also as a

brace and support to the united parts of the strap.

The strap is represented as a whole at 10, with an aperture 11 at one end and a buckle 12 at the other end, the buckle and aperture being near together when the strap is folded, as shown. The coupling-ring 13 is disposed in the fold of the strap.

The billet 14 of the strap to be attached is first passed through the aperture 11 and then engaged with the buckle 12 in the usual manner, the apertured end or side of the strap thus serving as a guard or shield to prevent the chafing of the horse by the buckle.

The keeper is represented at 15 and is disposed with one side between the folded portions of the strap and embracing one portion of the folded strap in position to receive the surplus portion of the billet 14 in the usual manner. The keeper is attached to both folds of the strap, and thereby materially strengthens and reinforces the same, and thereby materially increases the strength of the device.

The buckle is attached in the usual manner by folding the end of the strap around the rear bar of the buckle with the tongue projecting through the same, and the same fastening means, such as the threads by which the buckle-fold is secured, are utilized to secure the keeper at one end and the two folds of the strap, as shown in Fig. 2.

The coupling member and the buckle-guard are thus formed in one single piece and produce a simply-constructed and inexpensive device which is stronger and more durable than prior structures of this character and takes a less amount of leather to produce.

Having thus described the invention, what is claimed is—

A harness attachment comprising a continuous strap of homogeneous material which is provided at an intermediate point with a return-bend forming the major portion of an eye, a keeper rectangular in transverse and longitudinal directions, said keeper receiving one of the ends of said strap, the opposite sides of said strap being secured directly to the opposite sides of the said keeper, the intervening edge of the keeper comple-

ing the eye at the intermediate point of said strap, a ring passing through said eye, said strap having at one end a transversely-extending perforation and at its other end an eye, and a buckle retained by the last said eye.

In testimony that I claim the foregoing as

my own I have hereto affixed my signature in the presence of two witnesses.

ISAIAH McKNIGHT.
